UNITED STATES PATENT OFFICE.

WESLEY EMORY SITTERLY, OF AUBURN, NEW YORK.

DESIGN FOR A CHOPPING-KNIFE BLADE.

SPECIFICATION forming part of Design No. 26,282, dated November 17, 1896.

Application filed September 21, 1896. Serial No. 606,585. Term of patent 31 years.

To all whom it may concern:

Be it known that I, WESLEY EMORY SITTERLY, of Auburn, in the county of Cayuga, in the State of New York, have invented a new and useful Design for Chopping-Knife Blades, of which the following, taken in connection with the accompanying drawings, is a full, clear, and exact description.

Figure 1 is a side view of the chopping-blade, showing my design. Fig. 2 is a bottom view, looking at it from the cutting edge, these two views being deemed necessary to fully illustrate my design.

The leading feature of my design consists in a blade in the form of a quadrangle and fluted substantially vertically from and including the cutting edge up to a point near the

top thereof, and the lower edge rounded, the whole presenting a pleasing effect to the eye as a unitary article.

a is the blade, corrugated substantially vertically, as shown at *b*.

Having described my invention, what I claim, and what I desire to secure by Letters Patent, is—

The design for a chopping-knife blade, substantially as herein described and shown.

In witness whereof I have hereunto set my hand this 15th day of September, 1896.

WESLEY EMORY SITTERLY.

In presence of—

EDWIN L. AMIDON,

JAMES H. HOSKINS,

HOWARD P. DENISON.
